COMBINED TRIP AND THROTTLE VALVE.

1,069,434.

Specification of Letters Patent.

Patented Aug. 5, 1913.

Application filed May 14, 1912. Serial No. 697,129.

To all whom it may concern:

Be it known that I, PAUL W. KNAUF, a citizen of the United States of America, residing in Cynwyd, county of Montgomery, 5 in the State of Pennsylvania, have invented a certain new and useful Improvement in Combined Trip and Throttle Valves, of which the following is a true and exact description, reference being had to the accompanying drawings, which form a part thereof.

My present invention relates to trip valves and particularly to a combined trip and throttle valve adapted to be operated 15 through a nut and screw in normal operation and when tripped to close automatically and independently of the nut and screw.

The general object of the invention is to 20 provide an improved valve of the kind referred to.

One specific object of my invention is to provide such a valve with electromagnetic tripping means of desirable form, and a further object of the invention is to combine 25 this electromagnetic tripping mechanism with the valve mechanism proper in a simple, compact, and satisfactory manner.

The various features of novelty which 30 characterize my invention are pointed out with particularity in the claims annexed to and forming a part of this specification. For a better understanding of the invention however, and the objects accomplished there- 35 by, reference should be had to the accompanying drawings and descriptive matter in which I have illustrated and described forms in which my invention may be embodied.

40 Of the drawings, Figure 1 is a sectional elevation of one form of valve mechanism embodying my invention. Fig. 2 is an end elevation of the valve shown in Fig. 1. Fig. 3 is a diagrammatic representation of circuit connections for the electromagnetic tripping mechanism of the valve shown by Figs. 1 and 2. Fig. 4 is an elevation of a 45 portion of a modified form of valve mechanism embodying my invention. Fig. 5 is an end elevation of a portion of the mechanism shown in Fig. 4 and Fig. 6 is a diagrammatic representation of circuit connections for the electromagnetic tripping mechanism shown in Fig. 4.

50 In the drawings and referring first to the

construction shown in Figs. 1 and 2, A represents the valve casing body having inlet and outlet compartments connected by the valve seated port A'. The latter is controlled by the horizontally movable valve member B. As shown the valve member B is formed with a piston extension B' working in a balancing chamber A² located in the inlet compartment of the valve casing and connected with said compartment by a restricted passage or passages. The chamber A² is adapted to be connected with the outlet compartment of the valve casing through the port B² formed in the valve member B and controlled by the pilot valve 70 C. The latter is connected to an operating stem D projecting through the casing wall at one side of the valve and to a second stem portion E projecting through the wall of the valve casing at the opposite side of the valve. The stem E is provided with a piston enlargement E' of larger cross section than the stem D. The pilot valve and main valve are connected so that the pilot valve may have a restricted movement with respect to the main valve sufficient to close and open the port B². By virtue of the features of construction referred to, the main valve is substantially balanced when open, but the greater cross sectional area of the piston enlargement E' in comparison with the cross sectional area of the stem D gives the movable valve mechanism as a whole, a tendency to move into the closed position. The casing body A is formed at one side 85 with an aperture normally closed by the bonnet member F. The latter is provided with a suitable stuffing box for preventing leakage along the valve stem D, which passes through the body of the member F. 90 The bonnet member F is formed with arms F' integrally connected at their outer ends by a tubular portion F² which forms a guide sleeve for a sliding nut G screwed on to the threaded portion D' of the valve stem D. 100 At its outer end the valve stem carries an operating wheel or handle D². The sliding nut G is connected to the bonnet by a link connection consisting of a bell crank lever H fulcrumed at H' to the bonnet member F, and having the free end of one arm pivotally connected as by the pin I' to a link member I. The other end of the link member I is pivotally connected, as by the pin I², to the outer end of the sliding nut G. 110

The pivot pins I' and I^2 , as shown, are both located above the stem D' and so that when the rod G is in its outermost position, the axis of the pivot pin I' passes slightly below the plane including the axes of the pivot pins I' and I^2 so that the inward thrust of the rod G tends to lock the lever and link in a rigid position owing to the engagement of the lever H with the outer end of the bonnet sleeve portion F^2 . In this condition of the apparatus the valve may be opened, wholly or partly, and closed as desired by rotating the hand wheel D^2 so long as the parts occupy the position shown in Fig. 1. When the bell crank lever H is turned as it may be manually through the lever H^3 secured to the lever to move the pivotal connection I' above the plane including the axes of the pivotal connections I' and I^2 , the linked connection between the sliding nut and the bonnet is free to collapse and the valve then closes automatically under the loading force due, in the form of valve mechanism disclosed, to the unbalanced action of the fluid pressure within the valve casing on the stem enlargement E' . After the emergency closing of the valve in this manner the parts may be restored to their normal position by first rotating the valve stem in the closing direction until the long arm of the lever H and the lever I are brought into alignment. Thereafter on an initial reverse movement of the handwheel the pivotal connection I' drops thus restoring the locked condition of the link connection and the valve may then be opened as desired by the wheel. To permit of the tripping of the valve from a distance and through emergency means, I have provided an electromagnetic tripping mechanism which is supported on the valve casing bonnet as by means of a pair of bolts J passing through and secured in the apertures F^3 of the bonnet F' . As shown, the upper end of the bolts support a cross head K' which forms the lower end portion of the core of an electromagnet K' . The upper end portion of the magnet core is connected to the lower portion by the central core portion K^3 surrounded by the winding of the electromagnet. The armature of the electromagnet is in the form of an arm L formed of magnetic material and pivotally connected at K^4 to the member K' . The armature arm L is formed at its free end with cylindrical enlargement L' . In the normal condition of the apparatus shown in full lines in Fig. 1 the enlargement L' contacts with the upper end member K^2 of the electromagnet core and is retained in this position by magnetic attraction, the winding of the electromagnet being normally energized. The parts are so proportioned and arranged however, that when the electromagnet K' is deenergized, the armature

L will swing down into the dotted line position shown in Fig. 1. As the heavy free end L' of the armature L nears the position shown in dotted lines it impinges against the tripping finger formed by the arm H^2 of the bell crank lever H with sufficient force to move the pivotal connection I' above the dead center line and thereby permit the linked connection between the sliding nut G and the valve connection to collapse, whereupon the valve automatically closes. With the construction shown, the armature L stands nearly vertical in the normal condition of the apparatus and hence the magnetic force required to hold it in place may be comparatively small. 70

It will be apparent, of course, that various forms of circuit connections may be employed to control the energization and de-energization of the electromagnet K either manually or automatically. In the arrangement for this purpose shown in Fig. 3, K^5 and K^6 represent conductors connected to the terminals of the winding of the magnet K . A battery M connected between the conductors K^5 and K^6 provides the energizing current for the electromagnet. N represents a switch which may be located at any convenient place and which when closed forms a low resistance shunt about the battery M and thereby effectively deenergizes the magnet K . In Fig. 3 O' and O represent normally open switch contacts adapted to be closed by a speed governor P , and then closed to short circuit the battery just as the switch N does when it is closed. The governor P as shown, comprises a shaft P' which may be driven for instance by an engine supplied with steam passing through the valve shown in Fig. 1 and Fig. 2. The shaft P' which is hollow has axially mounted in it a sliding pin P^5 . The pin P^5 is connected with a sliding collar P^2 by the pin P^4 which passes through a slot P^7 formed in the hollow shaft P' . The sliding collar P^2 is connected by arms P^8 and weights or balls P^9 to a second collar P^2 secured to the shaft P' . With this arrangement, when the shaft P' attains a predetermined speed of rotation the outward throw of the weights P^9 and the consequent axial movement of the collar P^2 causes the sliding pin P^5 to force the switch contact O' into engagement with the contact O . This deenergizes the electromagnet K and trips the valve mechanism as hereinbefore described. 90

In the modified form of apparatus illustrated in Figs. 4, 5 and 6, the valve mechanism proper is shown as being identical with that shown in Figs. 1 and 2. The modified form of tripping mechanism shown in Figs. 4, 5 and 6 comprises a support L^4 secured to the posts J adjacent their upper ends. To the support L^4 is pivoted a member $L A$ 100

which may be practically similar in form to the member L first described. As shown in Figs. 4, 5 and 6, however, the free end of the member LA is adapted to have its center 5 of gravity swing over the axis of the pivotal connection L³ between the support L⁴ and the member LA as the arm approaches and leaves its normal position shown in full lines in Fig. 4. L⁶ represents a screw adjustably secured to the member LA and 10 adapted to engage a lug L⁷ carried by the support L⁴. A crosshead K¹⁰ secured to the upper ends of the post J forms the base of a pair of electromagnets KA. This cross 15 head is formed with bracket arms K¹¹ in which is pivoted a lever R. The latter forms in effect a pivoted armature for the electromagnet KA. The lever armature R is provided with a camming projection R³ 20 adapted to engage the cylindrical enlargement L⁵ of the member LA and move the center of gravity of the latter over the dead center line when the magnets KA are de-energized. S represents a counter weight 25 adjustably secured to the lever R so that the latter, while normally held by gravity in the position shown by Fig. 4, may be nearly balanced. With the devices S and L⁶ it is possible to adjust the apparatus that the 30 member LA may be cammed over the dead center line by a comparatively small force. To facilitate the return of the swinging arm LA to its normal position and to avoid all possibility of the weight being accidentally 35 thrown out of its normal position by vibration I prefer to provide the lever R with an arm R⁴ terminating in a hook R⁵ which is adapted to engage a tooth L⁸ carried by the arm LA when the magnets KA are de- 40 energized. As shown, the back of the hook R⁵ is beveled so that the hook does not tend to prevent the return of member LA into its normal position.

In the diagrammatic representation of 45 circuit connections shown in Fig. 6, K¹⁵ and K¹⁶ represent the conductors connected to the terminals of the windings of the electromagnets KA. The battery M or other source of current is shown as connected in 50 series in one of these conductors. N' represents a switch adapted to be manually actuated to close the energizing circuit for the magnets KA, and O and O' represent switch contacts controlled by a speed governor P as in Fig. 3. The switch contacts O and O' when brought together also close the energizing circuit of the magnet.

The electromagnet tripping mechanism shown in Figs. 1, 2 and 3 is somewhat simpler than that shown by Figs. 4, 5 and 6 but requires the magnet K to be normally energized. With the tripping arrangement shown in Figs. 4, 5 and 6, however, the magnets KA are normally deenergized. 65 With either form of apparatus disclosed the

valve proper and its trimming mechanism other than the circuit closing provisions are united in a simple compact self-contained structure in which the linked connection between the valve casing and sliding nut fall by gravity into the locking position on the proper manipulation of the hand wheel after an emergency closing of the valve. Owing to the manner in which electromagnetic tripping means are disposed the magnetic force required to hold the falling in its elevated position or to force it out of said position is comparatively slight. As the fulcrum of the lever H is fixed the force of the blow imparted to it by the falling weight does not depend on the extent to which the valve is open when the valve is tripped.

While in accordance with the provisions of the statutes I have illustrated and described the best forms of my invention now known to me, it will be apparent to those skilled in the art that changes may be made in the form of apparatus disclosed without departing from the spirit of my invention, 85 and that in certain cases some features of the mechanism may be used with advantage without a corresponding use of other features.

Having now described my invention what I claim as new and desire to secure by Letters Patent is,

1. In a combined trip and throttle valve mechanism, the combination with the valve casing, of a horizontally movable valve 100 mounted therein and having a stem projecting through the wall of said casing, said valve being unbalanced with a tendency to close, a nut in threaded engagement with said stem, a collapsible connection between 105 the casing and said nut, comprising a pair of members united by a pivotal connection and pivotally connected one to said casing and the other to said nut and provisions for arresting the downward movement of said 110 pivotal connection at a point slightly below the plane including the axes of the pivotal connections between said members and the casing and nut, and tripping means adapted to engage said collapsible connection and move said pivotal connection above said plane.

2. In a combined trip and throttle valve mechanism, the combination with the valve casing, of a horizontally movable valve 120 mounted therein and having a stem projecting through the wall of said casing, said valve being unbalanced with a tendency to close, a nut in threaded engagement with said stem, a collapsible connection between 125 the casing and said nut, comprising a pair of members united by a pivotal connection and pivotally connected one to said casing and the other to said nut and provisions for arresting the downward movement of said 130

pivotal connection at a point slightly below the plane including the axes of the pivotal connections between said members and the casing and nut, a weight adapted to fall from an elevated position into engagement with said collapsible connection and impart a blow thereto effective to move said pivotal connection above said plane, and means for releasably holding said weight in said elevated position.

3. In a combined trip and throttle valve mechanism, the combination with the valve casing, of a horizontally movable valve mounted therein and having a stem projecting through the wall of said casing, said valve being unbalanced with a tendency to close, a nut in threaded engagement with said stem, a collapsible connection between the casing and said nut, comprising a two-armed lever pivotally connected to said casing, a link united to one arm of said lever by a pivotal connection and pivotally connected to said nut and provisions for arresting the downward movement of said pivotal connection at a point slightly below the planes including the axes of the pivotal connections between the lever and casing and the link and nut, a weight pivoted to said casing and adapted to swing downward from an elevated position into engagement with the second arm of said lever and impart a blow thereto effective to move said pivotal connection upward above said plane, and means for releasably holding said weight in said elevated position.

4. In a combined trip and throttle valve mechanism, the combination with a valve casing of a valve mounted therein and having a stem projecting through the wall of said casing, said valve being unbalanced with a tendency to close, a nut in threaded engagement with said stem, a collapsible connection between the casing and said nut, comprising a bell crank lever pivotally connected to said casing, a link united to one arm of said lever by a pivotal connection and pivotally connected to said nut and provisions for arresting the movement of said pivotal connection in one direction away from the plane including the axes of the pivotal connections between said lever and casing and link and nut at a point closely adjacent said plane, and means for causing said pivotal connection to move from said point to the other side of said plane to thereby permit said connection to collapse, comprising a weight pivoted to said casing and adapted to swing down from an elevated position into engagement with the second arm of said lever member and thereby impart a blow to the latter, and means for releasably holding said weight in said elevated position.

5. In a combined trip and throttle valve mechanism, the combination with casing

and the valve, of operating means for the latter including a collapsible connection and provisions for automatically closing the valve when said connection collapses, means for bringing about the collapse of said connection comprising a weighted arm pivoted to said casing to turn about a horizontal axis and adapted when permitted to fall from an elevated position to engage said connection and bring about its collapse and an electromagnet supported from said casing and adapted to releasably retain said arm in its elevated position.

6. In a combined trip and throttle valve mechanism, the combination with the casing and the valve, of operating means for the latter including a collapsible connection and provisions for automatically closing the valve when said connection collapses, means for bringing about the collapse of said connection comprising a weighted arm pivoted to said casing to turn about a horizontal axis and adapted when permitted to fall from an elevated position to engage said connection and bring about its collapse and an electromagnet supported from said casing and adapted when energized to retain said arm in its elevated position by magnetic attraction.

7. In a combined trip and throttle mechanism, the combination with a valve casing comprising a body and a bonnet provided with a yoke, of a valve having a stem projecting through said casing, a nut in threaded engagement with said stem and slidably mounted in said yoke, supports secured to said yoke, a weighted arm pivotally connected to said supports, an electromagnetic device mounted on said supports for releasably holding said arm in an elevated position from which said arm swings downward when released, and a collapsible connection between said casing and said nut adapted to be struck and collapsed by said arm when the latter swings downward.

8. In a combined trip and throttle mechanism, the combination with a valve casing comprising a body and a bonnet provided with a yoke, of a horizontally movable valve having a stem projecting through said casing, a nut in threaded engagement with said stem and mounted in said yoke, vertical supports secured to said yoke, a weighted arm pivotally connected to said supports, an electromagnetic device mounted on said supports for releasably holding said arm with its center of gravity above and slightly at one side of the vertical plane passing through said axis whereby said arm will swing downward when released, and a collapsible connection between said casing and said nut adapted to be struck and collapsed by said arm when the latter swings downward.

9. In a combined trip and throttle mech-
